UNITED STATES PATENT OFFICE.

HERBERT W. LA MUNYON, OF CHEYENNE, WYOMING.

PORTABLE CLOSET.

1,425,391.

Specification of Letters Patent. Patented Aug. 8, 1922.

Application filed November 23, 1920. Serial No. 426,002.

To all whom it may concern:

Be it known that I, HERBERT W. LA MUNYON, a citizen of the United States, residing at Cheyenne, in the county of 5 Laramie and State of Wyoming, have invented new and useful Improvements in Portable Closets, of which the following is a specification.

The primary object of the present invention is to provide accommodation of its kind suitable to the needs of gangs of workmen whose work is located at places where such accommodations are not available or are distantly located.

15 In carrying out the invention, it is my purpose to produce a portable closet of a collapsible and foldable nature so as to occupy but little space when not in use and also so that it can be conveniently handled for transport.

A further object is the production of a device of this character which can be easily set up to produce a strong and efficient structure, and as readily collapsed, as well as 25 one in which the body or facing which includes the seat, the top and the door way, are constructed of fabric which may be folded around the supporting structure when the device is collapsed.

30 The foregoing, and other objects which will appear as the nature of the invention is better understood, may be accomplished by a construction, combination and operative arrangement of parts, such as is disclosed by 35 the drawings which accompany and which form part of this application.

In the drawings:—

Figure 1 is a perspective view of the improvement.

40 Figure 2 is a similar view of the frame work, the fabric facing or covering being removed.

Figure 3 is a sectional view on the line 3—3 of Figure 1.

45 Figure 4 is a sectional view on the line 4—4 of Figure 3.

Figure 5 is a sectional view on the line 5—5 of Figure 4.

50 Figure 6 is a sectional view on the line 6—6 of Figure 4.

Figure 7 is a sectional view on the line 7—7 of Figure 4.

Figure 8 is a perspective view of one of the cross places which support the seat.

55 Figure 9 is a similar view of the seat.

Figure 10 is a view showing the device collapsed and folded.

Figure 11 is a detail sectional view of a modified joint.

Figure 12 is a detail perspective view of 60 the spring hook and socket therefor.

The frame work of my improvement may be constructed of metal or of wood. When metal is used, pipe members may be employed.

65

In the showing of the drawings I have illustrated the frame work as constructed of wood in the nature of members of a similar cross sectional contour throughout.

The front corner posts are indicated by the 70 numerals 1 and 2 respectively, and the rear corner posts by the numerals 3 and 4 respectively. In the showing of the drawings each of the corner posts comprises two members of a similar length, the sections constituting 75 the front and rear corner posts 1 and 2, being hingedly connected, as at 5 on the outer sides of the said posts, while the hinges 6, which connect the sections of the rear posts 3 and 4 are arranged on the outer or rear 80 faces thereof. The post 3, adjacent to the top thereof has hingedly connected, as at 7, to the inner face thereof, one of the top timbers 8. The post 1, at the top thereof has its inner face provided with a socket 9 designed to receive therein a spring latch 85 tongue 10 provided on the free end of the top member or timber 8.

The inner side, at the top of the rear corner post 4 has hingedly connected there- 90 to, as at 11 the second top timber 12. The timber 12 has its outer or free end provided with a spring latch tongue to be received in a socket on the face of the corner post 4 op- 95 posite the corner post 3. The corner post 3 has hingedly connected to its lower corner, as at 15, a bottom timber 16. The outer end of the cross piece or timber 16 has a spring tongue to engage in a socket on the inner side face of the post 4.

100 On its inner face, at its top, the front corner post 2 has hingedly secured thereto, as at 19 a timber 20. The timber has its end provided with a spring tongue to be received in the socket at the upper corner of 105 the rear corner post 4.

The front corner post 1, at the top thereof has hingedly connected, as at 23, a timber 24. The free end of the timber has a spring tongue to be received in the socket on the side 110

of the timber which confronts the opposite front corner post. The front corner timber 2, at the bottom thereof has hingedly connected thereto, as at 27 a cross piece or timber 28, the latter having its free end provided with a spring tongue to be received in a socket on the corner post 1.

While I have referred to the cross connecting means for the corner posts as timbers, 10 it is not to be understood that this term implies the employment of heavy material. The so called timbers are in reality in the nature of bars or rods which, as previously stated, are of a similar cross sectional contour to that of the posts. The posts and the transverse connecting means therefor are square in cross section, and the frame work is light, so that the same can be conveniently handled in setting up the device, collapsing 15 the same, and carting the collapsed structure.

The lower sections on the inner and confronting faces of the front posts 1 and 2, and the rear posts 3 and 4 have opposed 20 sockets 31. In these sockets are designed to be received spring tongues 32 provided at the ends of timbers in the nature of cleats 33. On the upper face of each of the cleats 33 there is secured a plate 34 that has its 25 ends flanged upwardly, as at 35. The flanged ends, on the outer surfaces thereof, are designed to be contacted by the confronting faces of a pair of bars 36. The bars 36 have secured to the upper face thereof a fabric 37. 30 The fabric is centrally provided with an opening between the bars, and strips of fabric 38 are arranged adjacent to the edges of the fabric 37 and secured to the under face of the bars 36. The fabric 37 is of a length 40 to provide a depending portion or apron 38 over the outer bar 37.

Secured, in any desired manner, such as by screws or tacks, to the outer face of the front corner post 1, is a fabric sheet 39. 45 The sheet 39 provides the facing for the construction. The sheet may have its ends tacked or otherwise secured to the rear faces of the rear posts 3 and 4, and in a like manner secured to the outer face of the post 4, and to the outer face of the post 2. The strip is of a length to provide the same with an extension beyond the post 2, that forms a flap that provides a door 40. The door 40 has a plurality of openings therein, adjacent to the outer edge thereof to receive

a plurality of buttons 41, on the outer face of the post 1. The flap or door 40, at its upper edge has an extension 42 which is designed to be arranged over the top of the structure during rainy weather.

When the device is to be collapsed, the bars 36 to which the fabric seat 37 is connected are first removed, and the fabric folded around the bars. Thereafter the cleats 33 are removed. The fabric door is 60 unlatched, and the hinged transverse members carried by the several posts folded inward of the said posts. As these members are of a length less than the length of the sections constituting the posts, the posts may 65 be swung upon their hinges together with the said transverse members or timbers, and the cleats and the seat are then folded with the rest of the structure.

Each of the corner posts has secured thereto a guy rope 43. These guys are angularly directed from the structure, and are secured to pegs 44 which are forced into the ground surface. Thus the structure is protected 70 against collapsing by winds.

It is, of course, to be understood that the corner posts may not comprise hinged sections, and the said sections thereof may be coupled, as illustrated in Figure 10 of the drawings. Also if desired, the posts may 80 each comprise a single member, and it is thought that the foregoing description, when taken in connection with the drawings will fully set forth the advantages and operation 85 of the device. It is thought necessary, however, to state that the description and drawings refer to a satisfactory embodiment of the invention as it now appears to me and that I may make such changes therefrom as fall within the scope of what is claimed.

Having described the invention, I claim:

In combination with sectional collapsible frame and a fabric covering therefor including a door of a pair of spaced parallel horizontal cleats secured adjacent the lower end of said frame, plates secured to the upper face of said cleats and having flanged ends, bars arranged transversely on the cleats and contacting with the flanged ends of the plates, a fabric secured to the bars and having an opening formed therein, and an apron projecting from one end of said fabric and extending beyond one of said bars.

In testimony whereof I affix my signature.
HERBERT W. LA MUNYON.
